PRECISION SHARPENING DEVICE FOR
CUTTING BLADES

Joseph F. Vazquez, New York, N. Y.

Application October 27, 1944, Serial No. 560,533

6 Claims. (Cl. 51—221)

1

This invention relates to new and useful improvements in precision devices for sharpening scissors, shears, knives, surgical blades, and other cutting implements.

More specifically, the present invention proposes the construction of a device for holding an implement at the correct angle for drawing the cutting edge of the implement over the grinding edge of any of a wide variety of types of grinding stones or the like.

Still further, it is proposed to provide a device as aforesaid having supporting means holding the implement correctly while it is being drawn back and forth across the grinding apparatus.

Another object is to provide a device of the aforesaid type having a wide roller for rolling on a table or other surface, a rotatable rod for adjusting the angle of an implement-holding jig, and a jig rotatably secured to the rotatable rod.

Still further, it is proposed to provide an angle-determining jig for use with the sharpening device.

A further object is to provide a device as aforesaid for sharpening scissors.

A further object is to provide a device of the aforesaid type for sharpening a knife.

For further comprehensions of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of an implement to be sharpened, the sharpening device of the present invention, a sharpening stone, and a support for the sharpening stone.

Fig. 2 is an elevation of the sharpening device alone.

Fig. 3 is a fragmentary central sectional view of the sharpening device with a scissors assembled therewith.

Fig. 4 is a perspective view of an angle determining device, a pair of scissors associated therewith and a support for the device.

Fig. 5 is a view similar to Fig. 1 of the device equipped with a jig for holding a knife to be sharpened.

Fig. 6 is a rear perspective view of the knife-holding jig.

Fig. 7 is an elevation of a portion of a device constructed in accordance with a modification of this invention.

2

Fig. 8 is an enlarged section on the line 8—8 of Fig. 7.

The sharpening device, according to this invention, comprises a wide roller 10 which is journaled in a yoke 11. A cylindrical rod 12 is rigidly secured to the yoke 11 and this rod is provided with an axial mark 13.

Rod 12 telescopes in a barrel 14 and seats against a shoulder 15 therein. The barrel is reinforced with two axially spaced external bands 16 which may be shrunk or welded to the barrel, the lower band 16 has a threaded orifice in which is disposed a set screw 17 which when tightened, prevents rod 12 from rotating in the barrel. The barrel is conical exteriorly at its bottom and this conical portion is provided with a scale of degrees 18 which coacts with the mark 13 on the rod to indicate the angle of rotation of the rod 12 relative to the barrel 14.

20 The barrel is bored transversely through the upper band 16 at right angles to the set screw 17 providing an orifice 19. The outer ends of the orifice 19 in the upper band are countersunk. A threaded screw 20 extends through and beyond orifice 19, and has a conical portion 21 in one countersunk end of the orifice. A conical fitting 22 is freely disposed on the screw 20 and fits in the outer countersunk end. This fitting has an exterior flat end. A jig for holding a pair of scissors or other implement is mounted on the end of the screw 20.

25 It consists of two similar plates 23, oppositely disposed. Each plate has a flat portion 24 provided with a central orifice 25, a long flange 26 at one side and a short flange 27 at the opposite side. The plates are arranged so that orifices 25 are aligned and the short flange of one plate is adjacent the long flange of the other plate.

30 A pair of scissors 28 may be held in the jig by having the blade 29 to be sharpened disposed with its handle eye 30 on the screw 20 between the plates. A wing nut 31 is threaded on the end of the screw. When this nut is tightened up, the eye 30 is firmly squeezed between the plates 23 and the plates are firmly squeezed between the wing nut and the fitting 22.

35 However, even when the wing nut is tightly drawn up, the jig is free to rotate about the screw 20 as the conical portions disposed in the countersunk portions prevent the screw from being held against rotation relative to the barrel 14.

The operation of the device is as follows:

38 The pair of scissors is assembled with the jig and the jig is secured to the rest of the device 55 in the aforesaid manner. As viewed in Fig. 1,

the edge of the scissors to be sharpened will be disposed downwardly. This edge may be sharpened against whatever type of stone is desired. The operation of the devices is the same in any case, the only difference being that when the flat stone or cylindrical slip is used the abrasive appliance remains stationary while in the other case the flat edge presented to the scissor blade is continually changing as the stone rotates.

It is important, of course, that the edge to be sharpened be presented to the flat surface of the stone at the right angle. In a pair of scissors, this edge to be sharpened is inclined from the plane of the blade. This inclined edge must rest firmly over its entire surface against the flat face of the stone or it will not be sharpened correctly. Furthermore, in order to be sharpened, it must be drawn over the stone, maintaining full contact with the stone during this operation. The instant device is adapted to perform this operation.

The angle of the blade to be sharpened may be determined by resting the cutting edge against the stone and tilting the blade until the desired contact is obtained. During this tilting, the set screw 17 will be loose, the barrel rotating relative to the rod 12. Also, the roller 10 will be rested on a flat surface such as the flat surface of a table, and the sharpening stone must also rest on this flat surface or a flat surface parallel thereto. A suitable sharpening stone 32 is shown in Fig. 1 resting on a table 33. The roller is also shown resting on a flat surface 34 which may be a part of the table 33. Once the angle has been determined, the set screw is tightened so that this angle will be maintained during the sharpening operation.

If the angle of the edge to be sharpened is known, the jig may be disposed at the correct angle by means of the mark 13 and the scale 18. Sometimes the angle of the edge is not correct and therefore it is desired to determine a correct angle. For this purpose an angle-determining device 35 (Fig. 4) is provided for use with the sharpening device. This device 35 may be employed in all cases, if desired, as it insures a correct angle on the scissors. It includes a body 36, rectangular in shape, and formed of two flat bars of metal 37 separated at the top and bottom by two shims 38, all four parts being rigidly connected as by welding. The shims provide a rectangular slot 39 in which may be inserted a plate 40 having one angle-determining edge 41. Plate 40 is forced against the bottom shim by a set screw 42 threaded through an axial orifice formed in line with the slot 39. When set screw 42 is tightened up, it presses the plate 40 firmly against the shim so that the plate is held in its correct position. Body 36 is then placed on the table 33 and the flat side of the blade to be sharpened is placed against the edge 41 and made parallel therewith. Set screw 17 of the sharpening device is then tightened, and the angle of the edge to be sharpened is correctly determined.

Once the preliminary adjustment steps afore-described have been performed, the sharpening device is ready for sharpening. The jig is free to rotate, as aforescribed about the screw 20 so that the edge of blade 29 can be brought into contact with stone 32. The person sharpening the scissors holds on to blade 29 and draws it back and forth across the stone. This sharpens the blade. The blade is maintained in correct angular position on the stone by the roller 10 which rolls back and forth on the table as the blade is

moved back and forth. Thus a perfectly true sharpening of the blade is accomplished.

The sharpening device may also be employed for sharpening other implements than scissors. For instance, it may be employed for sharpening a knife. As a knife of the ordinary household type has no eye through which screw 20 may pass, it is proposed to provide a slightly different type of jig for mounting the knife on the device. 10 This is shown in Figs. 5 and 6 and is indicated generally by the reference numeral 43.

Jig 43 has a right angle body 44. One side is provided with an orifice 45 through which screw 20 passes, mounting the jig on the sharpening device similarly to the manner in which the scissor-holding jig was mounted. The other side is provided with two orifices 46 through which bolts 47 pass. A bar 48 is mounted on the bolts and secured thereto by wing nuts 49. The knife 50 to be sharpened is held between the bar 48 and the adjacent side of the body 44 between the bolts 47. It is sharpened just as the scissor blade was sharpened, the angle being determined in the same way.

25 A device constructed in accordance with a modification of this invention as shown in Figs. 7 and 8. It includes a base 51 adapted to rest on a table in place of roller 10. The base has a split sleeve 52 in which a cylindrical rod 53 is vertically secured. On rod 53 is telescoped a sleeve 54 having a clevis 55 at its top. A cylindrical guideway 56 is pivotally mounted in the clevis by screws 57. The guideway has a top longitudinal groove 58. A rod 12' is slidably disposed in guideway 56. Rod 12' has a tongue 59 disposed in groove 58, tongue 59 being formed by a strip secured in a groove in the rod 12'. Barrel 14 and the associated parts is secured to rod 12' similarly to the manner in which it was secured to rod 12.

The device of Figs. 7 and 8 operates just as did the device of Fig. 1 except that rod 12' slides in guideway 56 instead of moving with roller 10. Rod 12' has universal movement about the axes 40 of guideway 56 and rod 53.

While I have illustrated and described the preferred embodiment of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A device for use in sharpening an implement comprising a roller, a rod secured to said roller perpendicular thereto, a member connected to said rod for rotation relative thereto about said rod axis, a jig secured to said member for rotation relative thereto about an axis perpendicular to the axis of said member, said jig including two spaced plates, a screw extending through said plates and a nut on said screw whereby said implement may be firmly held between said plates and moved universally by said rotations about said two axes, and means for locking said member against rotation relative to said rod.

2. A device for use in sharpening an implement comprising a roller, a rod secured to said roller perpendicular thereto, a member connected to said rod for rotation relative thereto about said rod axis, a jig secured to said member for rotation relative thereto about an axis perpendicular to the axis of said member, said jig including two

spaced plates, a screw extending through said plates and a nut on said screw whereby said implement may be firmly held between said plates and moved universally by said rotations about said two axes, and means for locking said member against rotation relative to said rod, and a scale on said member and rod indicating the degree of relative rotation therebetween.

3. A device for use in sharpening an implement comprising a roller, a rod secured to said roller perpendicular thereto, a member connected to said rod for rotation relative thereto about said rod axis, a jig secured to said member for rotation relative thereto about an axis perpendicular to the axis of said member, said jig including two spaced plates, a screw extending through said plates and a nut on said screw whereby said implement may be firmly held between said plates and moved universally by said rotations about said two axes and means for locking said member against rotation relative to said rod, and a scale on said member and rod indicating the degree of relative rotation therebetween, each of said plates having a flat portion, a long flange at one side thereof and a short flange at the opposite side thereof, said plates being disposed parallel to each other with the long flange of each plate adjacent the short flange of the other plate.

4. A device for use in sharpening scissors comprising a yoke, a roller journaled in said yoke, a cylindrical rod secured to said yoke perpendicular to said roller, a hollow barrel telescoped on said rod for rotation relative thereto, about said rod axis, a jig secured to said barrel for rotation relative thereto about an axis perpendicular to the axis of said barrel, said jig including two spaced plates, a screw extending through said barrel and plates and a nut on said screw whereby said scissors may be firmly held between said plates with said screw passing through one eye of said scissors and said scissors may be moved universally by said rotations about said two axes, and a set screw for locking said barrel against rotation relative to said rod.

5. A device for use in sharpening an implement comprising a roller, a rod secured to said roller perpendicular thereto, a hollow barrel telescoped on said rod for rotation relative thereto about said rod axis, said barrel having a threaded ori-

fice and a set screw therein for locking said barrel against rotation relative to said rod, a jig secured to said barrel for rotation relative thereto about an axis perpendicular to the axis of said barrel, said jig including two spaced plates, a screw extending through an orifice in said barrel and through said plates, and a nut on said jig screw whereby said implement may be firmly held between said plates and moved universally by said rotations about said two axes, said barrel having a conical seat at each end of its jig screw orifice, and a conical fitting disposed on said jig screw in one of said seats, the head of said jig screw having a conical portion disposed in the other of said seats.

10 6. A device for use in sharpening a knife comprising a roller, a rod secured to said roller perpendicular thereto, a member connected to said rod for rotation relative thereto, a jig secured to said member for rotation relative thereto about an axis perpendicular to the axis of said member, said jig including a right angle plate, a plate adjacent one side of said right angle plate and secured thereto by two special screws, a screw extending through said member and the other side 20 of said right angle plate and a nut on said screw, whereby said knife may be firmly held between said two spaced screws and moved universally by said rotations about said two axes, and means for locking said member against movement relative to said rod.
